UNITED STATES PATENT OFFICE

OLIVER H. SCHLEMMER, OF CINCINNATI, OHIO

HOT WATER HEATING SYSTEM

Application filed May 11, 1926. Serial No. 108,391.

This invention relates to hot water heating systems, and has for an object the provision of means whereby to cause each radiator in the system to circulate exactly the amount of water required to perform the duty it is calculated to perform.

Another object is to provide such hot water heating system, wherein the need for much of the intricate calculation incident to selecting the different sizes of pipe is eliminated by employing safe maximum sizes of pipe and utilizing devices of my invention to insure the exact and proper circulation through each radiator.

Another object is to provide a device for use with hot water heating systems, by means of which there is eliminated the so-called short circuiting through one or more of the radiators.

Another object is to provide a device which positively and automatically controls a hot water supply to radiators, but which may be manually controlled, and also closed, without affecting the operation of the automatic mechanism, when such mechanism is again permitted to become operative.

These and other objects are attained by the means and methods described herein and disclosed in the accompanying drawings, in which:

Fig. 1 is a cross sectional elevation of a device of my invention.

Fig. 2 is an elevational view of a radiator and connections, having assembled therein a device of my invention.

Fig. 3 is a cross sectional view taken on line 3—3 of Fig. 1.

Fig. 4 is a view taken on line 4—4 of Fig.

Fig. 5 is a cross sectional view on line 5—5 of Fig. 1.

Fig. 6 is a cross sectional view of a simplified form of a device of my invention.

Fig. 7 is a diagrammatic elevation of a hot water system of my invention, showing the various radiators connected in various practical relationships to a system.

In heating systems employing hot water, much difficulty is experienced in so selecting the exact size of each length of pipe,

as to provide each radiator with the required amount of hot water. The proper circulation for a perfectly operating hot water heating system may be attained by determining the size of the various radiators, the temperature in the room in which the radiator is placed, the average temperature of water in the radiator, and the maximum temperature degrees drop which the water is to undergo while passing through the radiator and the height of the radiator above the boiler. Given these figures, it is possible to calculate the exact size of pipe required in each part of the system, and to calculate the resistance to the flow of water through said pipes. In such systems hot water circulates through the several radiators, and in giving off its heat, becomes cooler and heavier, and passes through return pipes to the boiler. When the inlet is connected to the top of a radiator, it may be stated that the hot water circulates through the radiator through the agency of a force equal to and resulting from the difference in weight between the cooler water passing out of the radiator and the hot water entering the radiator, measured, as known columns of hot and cool water in the system, on the vertical distance between the center of the water space in the boiler and the center of the radiator in the system. In order to have each radiator in a system give off the desired number of heat units per unit of time, the supply must be accurately regulated. If too much water passes through one radiator in the system, the system may become short circuited, so that other radiators will receive too small a supply, or none at all, and a lack of uniformity in heating in the system will result therefrom. To attain a perfectly operating hot water system by using the required size of pipe at each point, entails calculation so intricate and so difficult of practical embodiment as to result in few perfectly installed systems.

In the system of my invention, I have provided a device whereby safe maximum sizes of pipes are employed, so as to insure ample, and in some cases, excessive pressure at each

2
radiator or group of radiators. The single radiator, or groups of radiators, are then governed by a device of my invention, whereby only the required supply of hot water is delivered to each radiator or group of radiators.

This device does not operate thermostatically, but employs a supply control means which is automatically regulated and tends to assume a position of balance between opposed forces within the system. These opposed forces comprise the pressure of the hot water supply on the one side and on the other side a force resulting from a difference in the weights of two known columns of water of different temperature, the weights of which columns are opposed one to the other.

In order to clarify the explanation of structure and operation of my device, I have shown a simplified operative form in Fig. 6, which will be explained before describing the commercial embodiment thereof.

Referring to Fig. 6, 10 represents a hot water supply pipe into which the bottom of a cylinder 11 is screw-threaded. The cylinder 11 has a bottom wall 12, having a cup structure 13, provided with a plurality of vertically spaced opposed perforations 14, through which hot water from supply pipe 10 must pass in order to enter the cylinder 11. A cylindrical sleeve 15 may be reciprocated vertically interiorly of the cup 13, and is of such diameter as to give clearance between the outer wall of the sleeve 15 and the inner wall of cup 13. This clearance space 16 permits seepage of hot water from the supply pipe 10, when the sleeve 15 is in position substantially closing the perforations 14 in the cup. This provides a film of water between the sleeve and cup, which precludes binding of the members one upon the other. It will be apparent, therefore, that when the sleeve 15 is lowered slightly, the uppermost perforations 14 will be free to permit a hot water supply to flow freely therethrough into the cylinder 11, and that as the sleeve is moved downwardly, to uncover all of the perforations, a maximum of hot water will pass through the perforations into said cylinder. When the sleeve is in the position shown, the flow is reduced to a minimum. Suitably secured to the center of sleeve 15 is a rod 17, by means of which the sleeve is raised and lowered. The rod 17 passes through and is secured to a hollow float 18, and has a guide bearing in an open web 19 secured adjacent the top of the cylinder. Stop 170 on rod 17 limits upward movement of the float as it strikes web 19. Downward movement of the float is limited by the lower end of rod 17 striking the base of cup 13. The circumference of the float 18 is slightly less than the inside circumference of cylinder 11, so that there

is no frictional binding between said members, and for the members to permit a slight seepage of water therebetween. The entire cylinder above and below the float 18 is filled with water, and the weight of sleeve 15, float 18, and all the parts associated with the rod 17, is such that they are in a position of submerged balance. Cover flange 21 forms a closure for the top of cylinder 11, and has a reduced threaded coupling 22 which is connected to the bottom of a radiator by a suitable pipe. Port 23 in the cylinder 11 receives a hot water supply pipe 24, which leads to the top of the radiator. The operation of the device is as follows:

Hot water begins to circulate upwardly through perforations or ports 14, into cup or valve seat 13, into the chamber comprising the interior of cup 13 and the interior of the cylinder 11. Part of the hot water may find its way upwardly, past the float through the space 25 between the float and the cylinder wall, but the larger portion passes out through port 23 and pipe 24, and from thence into the top of the radiator. The water in the radiator being cooler and hence heavier than the incoming hot water, the cooler water immediately tends to find its way through opening 22 into the cylinder, so that there is immediately created a cooled water chamber above the float 18, and a consequent pressure tending to push the float down, thereby moving the sleeve of valve 15 downwardly and opening up a greater number of the ports of perforations 14 in the valve seat 13. At the time pressure has been built up in the system generally, particularly in the hot water chamber constituted by that portion of cylinder 11 below the float 18, it will immediately effect a balancing of the float 18 at such a position as to retain valve 15 sufficiently open to admit just the required pressure for maintaining the balance. This permits the proper amount of hot water to be circulated through pipe 24 to the radiator. By the simple mechanism shown and described, there is effected at all times a positioning of the valve 15 for admitting the required supply of hot water to the radiator. The adjustment of the valve is automatically controlled through the agency of the different weights of selected known columns of water having different temperatures. The one column is the cooled water vertically through the radiator and the other column is the vertical hot water column from the device to the top connection to the radiator. When the average temperature of the water in the radiator is low, the water which is in communication with the cylinder above the float will be colder and hence heavier than under normal conditions. The water, being colder and heavier, will push the float 18 downwardly, thereby open-

ing more of the valve ports 14 and permitting the hot water supply in member 10 to supply more hot water to the radiator through pipe 24. After the hot water has 5 circulated for a time, the average temperature in the radiator will rise under normal conditions. The column of water through the radiator is then of higher average temperature and consequently lighter in weight. 10 The float 18 will rise and valve 15 will reduce the supply of hot water through pipe 24. This results in the water in the radiator seeking an average temperature determined by the size of pipe 24 connecting the device 15 with the top of the radiator. The size of this connection is so selected that the friction of total connection 24 from the device to top of the radiator is equal to the balancing pressure in hot water chamber beneath float 18. The size of connection 24 20 is chosen for carrying a full load for attaining a maximum chosen drop in temperature between the cooled water leaving the radiator and hot water supply when the 25 temperature of the hot water supply is at a predetermined maximum.

The commercial embodiment of the device of my invention, as is best shown in Fig. 1, operates in substantially the same manner 30 as the simplified form just described, but has added thereto certain structure for effecting manual control within given limits, and also for shutting off a given radiator. In addition to this, there are provided means 35 whereby the devices may all be manufactured in but few sizes and adjusted at the factory for the particular duty required of them. Referring to Fig. 1 a casing 25 has a hollow interior 26, within which is disposed a separate passage 27, provided by an integral interior wall 28, connected to the wall 29 and extending to the bottom of the casing 30. Communication between passage 27 and the interior 57 is uncontrolled 40 as hereinafter described. The wall 28 is formed relatively thicker adjacent its base through which perforation 31 extends; this thickness being added thereto for the sole purpose of providing a longer restricted 45 perforation between the passage and the interior of casing 25 for drainage purposes. The lower end of casing 25 is developed into a coupling 33 for receiving a hot water supply pipe 34. A cylindrical valve seat 35 has a plurality of rows of opposed ports 36. 50 A sleeve-like circular valve 37 surrounds the cylindrical valve seat 35, and is reciprocable vertically thereover for opening and closing the ports 36. The valve and valve seat have a slight clearance therebetween, so as to permit a film of water to remain therebetween, which precludes binding of the members one upon the other, and also prevents absolute closure of the valve. The valve 37 is suspended from the bottom of a cylindrical 55

float 38 by means of a hanger 39. The securing means for attaching the hanger to the float are developed into a conical point 40, so that when the float is in its lower position only the point 40 will contact the 70 upper face 41 of the valve seat member 35, so that any pressure within the interior 26 of the casing, may exert its force upon the entire lower face of the float. A cylinder 42 houses but does not contact float 38, and 75 has a funnel-shaped outwardly tapering flange 43, and a lip 44 which is secured upon the top flange 45 of the casing 25 by being clamped between said flange and the cover plate 46 of casing 25. A plurality of 80 screws 47 extend through top plate 46, lip 44, and flange 45, binding the parts one upon the other. The tapered flange 43 has a plurality of spaced perforations 48 disposed about its circumference. One of these 85 openings designated at 49 (see Figs. 1 and 5), provides communication between the top of passage 27 and the interior of cylinder 42 above the float 38, forming chamber 57. A rotatable closing member 50 has a flange 90 51 provided with perforations 52, which may be brought into registry with perforations 48 in the flange 43. The member 50 has a flat top 53, which is perforated to receive a guide stem 54 carried by the float 38. 95 Means hereinafter described are provided to limit the rotation of the closing member 50, so that perforations 48 may be completely opened by bringing perforations 52 into registry therewith (as shown in Fig. 5) 100 or completely closing the perforations by moving the member 50 and disposing perforations 52 therein completely out of registry with perforations 48, so that the flange 51 of member 50 will completely seal the 105 perforations 48. An upwardly struck integral pocket 55 extends above and is always in open communication through perforation 49 with passage 27, and an opening 56 permits constant communication between the 110 chamber 57 above the float 38 in cylinder 42 and passage 27. A spring tension member comprises an annular portion 58, having a plurality of upwardly turned resilient arms 59, which are fixed against rotation on the lower face 60 of the top member 46 of the device, while the annular portion 58 presses downwardly upon the top 53 of closure member 50. By this means the closure 115 member is retained upon its seat on the 120 flange 43 of cylinder 42.

A hollow angular housing member 61 is secured to the top face of the movable member 50, which has perforation 62 to provide a guide bearing for receiving the guide stem 125 or rod 54 of float 38. The upper end of rod 54 is pointed to present a single point of contact to the top of housing 61 which serves as an upper limit stop. A needle perforation 63 extends through angular housing 61 to 130

eliminate the possibility of air becoming trapped in the top of the housing and impeding free movement of the parts.

Means are provided for rotatably actuating the angular housing 61, so that it may impart its movement to movable member 50 for varying the size of the openings between stationary flange 43 and the movable flange 51 on member 50. This movement is effected by means of a lever 64 having an angular perforation 65 therein for receiving the housing 61. The lever 64 has an elongated aperture or slot 66 extending in the direction of its length. A crank 67 is journaled in the closure flange 46 and has its crank arm 68 disposed interiorly of the cylinder above member 50. Pin 69 on crank arm 68 enters slot 66 so that when the crank 67 is turned the lever 64 will impart movement through housing 61 to member 50 for controlling communication through perforations 48 and 52. A suitable packing gland 70 permits passage of the stem of the crank 67 to the exterior of the device, where a regulating handle 71 is attached thereto by any suitable means. The regulating handle 71 has a depending lug 73 which may abut limit stops 74 and 740 on arcuate member 75. Screws 76 serve to secure the member 75 to the top face of the cover flange 46. The stop 74 is integral with the arcuate member 75 and constitutes the "off" limit stop. The stop 740 has an angular extension 741 and is secured in adjusted positions on arcuate member 75 and cover flange 46 by the screw 760. A plurality of tapped holes 77 in member 75 are provided in order to effect adjustment of the stop 740. The stop 740 is initially set at the factory and in this way a number of permanent adjustments may be made on devices of a given size, so that said devices may be made suitable for a number of different maximum capacities by shifting the position of member 51 thereby restricting the actual opening through orifices 48 and 52. One object of this is to eliminate the necessity for manufacturing the devices in a plurality of sizes. The principal object is to provide means to permanently govern the full capacity of the device to permit of the use of standard sizes of pipe from outlet 78 to the radiators. The handle member 71, crank 67, and lever 64 constitute a manual adjustment for controlling circulation from chamber 26, which constitutes the hot water chamber, through outlet 78 which is connected with radiator 79 by riser 80.

Referring to Figs. 1 and 2, it will be noted that the hot water supply in pipe 34 enters the bottom of the device and passes through ports 36 governed by valve 37. The water then finds its way through chamber 26, perforations 48 and 52, then upwardly through riser 80 into the top of radiator 79. As the

radiator 79 gives off the heat of the water, the water becomes cooler and circulates to the bottom of the radiator and then out through cold water return pipe 81. It will be noted, however, that the bottom of passage 27 connects with the bottom of radiator 79 through a suitable section of pipe coupled to the radiator and threaded nipple 82 on the casing. A stop cock 83 is inserted between the radiator and the bottom of passage 27 for effecting further adjustment of the device. The water in the radiator 79 is coldest at the bottom and warmest at the top, so that the average temperature of the column of water in the radiator is lower than the column of hot water in the riser 80. The entire casing 25 is always filled with water as is also the passage 27, which is in open communication therewith through ports 49 and 56. The weight of the column of water in the radiator transmits pressure to the water in passage 27 and the water in cooled water chamber 57 above the float 38. The lesser weight of the column of hot water in riser 80 and chamber 26 below the float 90 transmits its weight in the form of an upward pressure on the bottom of the float 38. The resultant pressure of these two columns provides a downward pressure on the float.

This tends to move float 38 downwardly opening ports 36 to admit a counterpressure from supply pipe 34, thus tending to balance the float. This counterpressure, as relates to the circuit, is consumed in friction in moving the hot water therethrough (from chamber 26, through orifices 48 and 52, riser 80 into the radiator). A part of the pressure in either chamber is lost in the resistance to seepage between float 38 and cylinder 42 when the float tends to seek a position of balance.

As the temperature of hot water in pipe 34 and chamber 26 rises, the radiator will naturally give off more heat. This results in a greater difference in temperature between the hot water and cooled water columns. This results in a greater downward pressure on the float and a tendency to further opening of ports 36, to provide a correspondingly greater counterpressure. It will be apparent that the higher the temperature of the hot water supply becomes, the greater will be the supply of hot water to the radiator. The average difference in weight between the known cooled and hot water columns in the average radiator amounts to about three-hundredths of an ounce per square inch on top of the float, from which it is readily apparent the controlling pressures in the device are minute.

In Fig. 7 there is shown a diagrammatic outline of a complete system, in which the radiators are disposed at different elevations and spaced at different distances from the supply pipes 34 and return pipes 81.

In this system all of the supply pipes 34 may be of safe maximum sizes to provide the required quantity of water. The devices or mechanisms contained within the casing 25, which may now be indicated by reference numeral 85, are positioned between the pipe 34 and riser 80 of each radiator or group of radiators. An excess of pressure from the boiler through supply pipe 34 will not result in an excessive amount of circulation through the radiator because, as previously explained, the regulators 85 will each permit only the desired amount of water to circulate through it, and it will automatically adjust itself to supply each radiator its required amount of hot water. Attention is drawn to the fact that a pump may be used in the system for producing pressure artificially, but the regulators 85 will function in their usual manner, regardless of this pressure.

At the extreme right of Fig. 7 there is shown a single radiator, in which the cool water return pipe 81 is taken off from the same end of the radiator as receives the hot water supply. In this case the pipe 81 is connected intermediate the radiator and the stop cock 83. Adjacent the last mentioned radiator is shown a pair of radiators at different elevations which are controlled by a single regulator 85. In places where the ordinary flat ceiling radiators are used, and the depth of the water in such radiators 790 is slight, the regulator 85 is positioned 30 at some distance beneath the radiators and artificial known heads or columns of hot and cooled water are provided by using risers such as 800 and 810. It is understood, of course, that the regulators 85 are for the sake of convenience, ordinarily positioned at the bottom of the radiator. It is not essential, however, that they be positioned on a level with the bottom of the radiator, as is demonstrated in the case of the ceiling radiators, where a known artificial head or column is employed for attaining the known columns of water at different temperatures which are balanced against each other to regulate the circulation through the radiator.

As heretofore explained, the manually operated handle 71 may be used when it is desired to decrease the flow to the radiator. This is accomplished by moving handle 71 55 toward the stop 74 which partially closes perforations 48 and 52, thus shutting off some of the supply. The stop cock 83 may be partially closed, thereby reducing the amount of seepage upwardly between the float 38 and cylinder wall 42, so that the pressure in cooled water chamber 57 is increased and the float will tend to move downwardly, opening the ports 36. From the foregoing it will be apparent the handle 71 is for manual adjustment to shut off

the radiator. The stop cock 83 provides an additional adjustment by means of which the supply of hot water may be increased, enabling the radiator to give off more heat. This is sometimes desirable after installation to remedy the defect of too small a radiator.

The weights or washers 20 are utilized for the purpose of effecting a submerged balance of the float and are used to correct slight variations in weight of the parts which may occur in commercial production. I prefer to effect this submerged balance of the float in cold water.

I do not limit myself to the exact details of structure as shown, as they may be varied within the scope and spirit of the invention.

What I claim is:

1. In a hot water heating system the combination with a radiator, of a hot water supply pipe, a riser for feeding hot water under pressure from said supply pipe to the radiator, predetermined portions of the riser and radiator serving as means for containing columns of water of known height in the system, and an automatic regulator communicating with the hot water supply pipe and with the radiator, said regulator comprising a slidable valve to control the flow from the hot water supply pipe to the radiator and means directly connected and movable therewith and subjected to pressures in the system in both directions, said means yielding thereby moving the said supply controlling valve and serving to effect a balance between the pressure resulting from the difference in weight between a known column of hot water in the riser and a known column of relatively cooled water in the radiator, and the pressure controlling the supply of hot water to the radiator.

2. In a circulating hot water heating system the combination of a source of hot water supply, a radiator, means providing communication between the source of hot water supply and the radiator, a return pipe between the radiator and source of supply, a regulator casing interposed in the connecting means between the source of supply and the radiator and having communication with the lower portion of the radiator, means in the casing adapted to be balanced between opposed pressures exerted by a resultant pressure due to the difference in weight of columns of hot and cooled water of known height contained in the supply means and radiator and by the pressure of the hot water supply and a valve operable by said balancing means for regulating the hot water supply to the radiator.

3. In a hot water heating system, a radiator, a hot water supply pipe communicating with the upper portion of the radiator, and a low differential pressure metering device

connected with the lower portion of the radiator and the hot water supply pipe, said radiator and supply pipe, above the metering device, serving as means to contain two vertical columns of water of known height; the metering device comprising a submerged float, subjected on its top to pressure due to the weight of one of said known columns of water and on its bottom to the combined pressures of the weight the other of said known columns of water and the pressure of hot water in the supply pipe, and a valve movable with the float and controlling the flow of hot water from supply pipe to the casing.

4. In a circulating hot water heating system, a radiator, a hot water supply pipe and a differential pressure type metering valve connected to said radiator and supply pipe for automatically regulating the flow of hot water from said supply pipe to said radiator, said metering valve including a submerged element and a control valve proper, the submerged element being subject to differential pressures in the system and directly connected to the valve proper for effecting movement thereof, the differential pressure actuated member constituting the sole means for effecting movement of the valve proper.

In testimony whereof, I have hereunto subscribed my name this 10th day of May, 1926.

OLIVER H. SCHLEMMER.
